UNITED STATES PATENT OFFICE.

ROBERT DUNCAN, OF KNOXVILLE, TENNESSEE.

MECHANICAL CALCULATOR.

SPECIFICATION forming part of Letters Patent No. 591,332, dated October 5, 1897.

Application filed February 8, 1897. Serial No. 622,532. (No model.)

To all whom it may concern:

Be it known that I, ROBERT DUNCAN, of Knoxville, in the county of Knox and State of Tennessee, have invented a new and Improved Mechanical Calculator, of which the following is a full, clear, and exact description.

This invention relates more particularly to devices for computing the charge to be made for a guest at a hotel; and the object is to provide a simple device by means of which the hotel clerk can quickly ascertain the amount of a guest's bill without resorting to mental figuring.

The invention comprises a rotary calendar and cost-price disk and a rotary rate-disk.

The invention further consists in the construction and novel arrangement of parts, as will be hereinafter fully set forth, and pointed out in the claims.

Reference is to be had to the accompanying drawings, forming a part of this specification, in which similar characters of reference indicate corresponding parts in all the views.

Figure 1 is a front view of a device embodying my invention. Fig. 2 is a section on the line 2 2 of Fig. 1. Fig. 3 is a front view of a device of modified construction. Fig. 4 is a rear view thereof, and Fig. 5 is a section 30 through the line 5 5 of Fig. 4.

Referring first to the example of my invention shown in Figs. 1 and 2, 1 and 2 indicate the front and rear walls of a casing separated at the edge by a strip 3. Arranged to rotate between the front and rear walls 1 and 2 of the casing is a disk 4, having a calendar or figures "5" arranged around its periphery on its upper surface, and designed to indicate the date of the days of a month. The top wall 1 of the casing is provided with openings 6, through which the several figures may be seen.

Arranged on the disk 4 within the circle of figures "5" are several circular rows of figures "7" for indicating the number of days, and within these several rows of figures indicating the number of days are several other rows of figures "8," indicating the amount of a bill. The several figures of each row 7 and 8 are divided by radial lines, printed or otherwise marked on the disk 4.

Mounted to rotate on the upper wall 1 of the casing is a rate-disk 9. The rate-disk 9

may be rotated independently of the disk 4, and as a means for rotating the disk 4 I provide a finger-piece 10, which has a hub-like portion extended through a central opening in the disk 9 and having an angular portion engaging in a correspondingly-shaped opening in the disk 4. Therefore it will be seen that by rotating the finger-piece 10 the disk 4 may be rotated and that the disk may be rotated on the finger-piece.

The rate-disk 9 is provided with a peripheral opening 11, through which the several sets of the figures "7" may be seen, and inside of this opening 11 the said disk 9 is provided with a keystone-shaped opening 12, through which several sets of the figures "8" may be seen. At one side of the opening 12 the rate in dollars and fractional marks are printed on the disk 9, and at the opposite side of said opening 12 is a series of marks indicating the cost for fractional parts of days.

At one side of the opening 11 are printed the letters "B," "D," "S," "L," and below the said opening are also printed the letters "B," "D," "S," "L." The first-named letters are arranged with the "B" in line with the outer line of figures 7. The next letter, "D," is arranged in line with the next line of figures 7. The letter "S" is arranged in line with another inner set of circumferentially-arranged figures 7, and the letter "L" is arranged in line with the inside set of circumferentially-arranged figures. In the second series of letters the letter "B" is arranged to be moved into coincidence with one radial line of figures 7, the letter "D" coincident with another radial line of figures 7, and so are also the letters "S" and "L." These letters are intended to indicate the quarters of a day—that is, the letter "B" will indicate "breakfast-time," the letter "D" indicating "dinner-time," the letter "S" "supper-time," and the letter "L" "lodging-time."

In operation the guest when entering the hotel registers at one of the four divisions of the day—that is, should he arrive at breakfast-time and partake of the same his bill will date from that time. When leaving, he is booked up to the last meal or lodging. To ascertain the amount of the bill, the clerk will set the disk 4 so that the calendar-date upon which the guest arrived will be opposite the

star or other indicator 13, and then he will move the rate-disk 9 around to the right until the opening 11 is coincident with the date upon which the guest leaves. He then takes 5 the number of days as shown on the circle of figures 7 coincident with the letter indicating the time of day of his arrival, and then he observes the figure in said line which is in the radial line of the letter indicating the 10 time of day of departure, and then by referring to the rate-disk the amount of the bill is quickly ascertained. For example, a guest registers on the fifth day of the month at dinner and leaves on the tenth day of the month 15 at supper time. The fifth day of the calendar is set opposite the pointer 13, and then the rate-wheel is moved around to bring its opening 11 opposite "10" of the calendar. Following the circumferential line D to its 20 joining with the radial line S it will be seen that five and one-half days are registered. Referring to the rate-column 14 at three dollars and fifty cents per day and following the curved line therefrom to a point coincident 25 with the radial line from the figure "5," printed on the disk 4 inside the several rows of cost-figures, it will be seen that "\$17.50" is indicated—that is, this "\$17.50" gives the price for five days of board at three dollars 30 and fifty cents per day; but as there is still one-half a day to be added the circular line opposite the "\$3.50" is to be followed to the column showing fractional parts of the day and in the space marked " $\frac{1}{2}$," where "\$1.75" 35 will be found. This, added to "\$17.50," makes "\$19.25," the total amount of the bill.

In the example of my improvement shown in Figs. 3, 4, and 5 I have designed the device as a weekly calendar, operating, however, on the same principle as the one first described. In this example the disk 15 has the days of a week printed around its edge, and the letters thereof may be seen through openings 16 in the front wall 17 of the casing. 40 This front wall 17 has printed upon it a series of spaced circular lines and a series of spaced radial lines. In the spaces formed by the intersecting circular and radial lines are printed figures 18, indicating the number of 45 days. Mounted to rotate on the front wall 17 is a disk 19, having an opening 20 in its edge, near one side edge of which are printed the letters "B," "D," "S," "L," and adjacent to the lower edge of which are printed 50 the letters "B," "D," "S," "L." These letters are for the same purpose and operate in 55 the same manner as the letters before described.

Mounted to rotate with the disk 19, but on 60 the opposite side of the disk 15, is a segmental disk 21. These two disks 19 and 21 are each connected to the head portion of a shaft 22, mounted to rotate in a hole formed in the central portion of the front wall 17 of the 65 casing, and the disk 15 is mounted to rotate on this shaft. The disk 15 is made in the form of a wheel—that is, it has a rim upon

which the days of the week are printed—and it has radial spokes, on the rear side of which are printed figures indicating the price per 70 day, and upon the disk 21 is printed a series of figures representing the price for fractions of a day, such as one-fourth, one-half, and three-fourths of a day. One of the openings 16 in the front wall 17 of the casing is 75 somewhat elongated, as shown at 23, and the rim portion of the disk 15 is provided with depressions or holes into which the point of a pencil or similar device may be inserted to rotate said disk—that is, by inserting a pencil 80 in the depression or hole at one end of the slot 23 the disk should be rotated until the pencil strikes against the other end of the slot, and this will give a proper length of movement to the disk to bring the letters indicating the several days of the week into the sight-openings.

In the operation of this device the disk 15 will be rotated to bring the date of arrival of a guest opposite the pointer 13. As here 90 shown, "Tuesday" is indicated. Assuming that the guest has arrived at breakfast-time on Tuesday and departs at supper-time on Wednesday, the opening 20 of the disk 19 will be turned opposite the letters indicating 95 "Wednesday." Following the circular row of figures coincident with the letter "B" to the space in radial line with the letter "S" it will be seen that one and three-fourths days are indicated. Assuming the price per day to be 100 five dollars, the clerk by reversing the instrument will note that the outer line of figures in line with the space marked "1" indicates "\$5.00," this being in line with the figures indicating "\$5.00" on the adjacent spoke of 105 the disk 15; but as this only gives the price for one day the price for three-fourths of a day will be found at the outer edge of the last column of figures printed on the disk 21, which indicates "\$3.75." This, added to the "\$5.00" 110 before ascertained, gives "\$8.75," the amount of the bill for one and three-fourths days.

The calendar-table on the device shown in Fig. 1 indicates thirty-one days, because there are more months in a year composed of thirty-one days than of any other number. In calculating the time in a month of less than thirty-one days, where a guest registers in one month and leaves in the following month, the calendar-disk is advanced the number of 115 days the month is short of thirty-one. For instance, a guest registers on the 28th of June and leaves on the 2d of July, the calendar would be set to the 29th instead of the 28th. This applies only where a guest arrives in one month and departs in the following month and only in months having less than thirty-one days.

While I have described my device as particularly adapted for hotel purposes, it is obvious that it may be used as a computing-scale for other purposes—such, for instance, as ascertaining the amount due a workman—and obviously by slight changes in the sys- 130

tem of lettering and figuring it might be employed as an interest table or computer.

Having thus described my invention, I claim as new and desire to secure by Letters Patent—

1. A mechanical calculator, comprising a rotary calendar-disk, the said calendar-disk having figures indicating the numbers of days and also a series of figures indicating total amounts, and another disk mounted to rotate relatively to the first-named disk and having an opening in its edge to disclose figures indicating the number of days, and having letters printed on one side of said opening indicating fractions of a day and also having letters at the lower edge of said opening indicating the fractions of a day, a series of figures indicating day-rates printed at one side of another opening in said last-named disk, and a series of figures printed at the opposite side of said last-named opening indicating the cost-price for fractions of a day, substantially as specified.
2. A mechanical calculator, comprising a casing having a circular row of slot-openings through its front wall, a disk mounted to rotate in said casing and having day-dates printed near its periphery to be disclosed through said slot-openings, the said disk also having a series of annular rows of figures indicating numbers of days and also having a series of annular rows of figures indicating

total amounts, and another disk mounted to rotate relatively to the first-named disk and having an opening in its edge, on the inner 35 and one side edge of which are printed the letters B, D, S, L, the said other disk being also provided with a keystone-shaped opening adjacent to one edge of which is printed a series of figures indicating the rate of cost 40 per day, and having printed adjacent to the other side of said opening a series of figures indicating the cost for fractions of a day, substantially as specified.

3. A mechanical calculator, comprising a 45 casing, a wheel-shaped disk having day-indicating marks near its edge, designed to be disclosed through openings in the casing, radial spokes on said disk having per-day cost-marks, a series of figures on the casing 50 indicating total amounts, a series of figures on said casing indicating total numbers of days, and a disk having an opening in its edge through which day-indicating figures may be seen, one of said openings being 55 longer than the other so that an instrument may be moved along it while engaged with the disk for rotating it, substantially as specified.
